US00D755206S

(12) **United States Design Patent**
Lee et al.

(10) **Patent No.:** **US D755,206 S**
(45) **Date of Patent:** ** May 3, 2016

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Yu Kyung Lee**, Seoul (KR); **Ji Hyun
Jeon**, Suwon-si (KR); **Ye Kyung Yoo**,
Seoul (KR); **So Young Yun**, Seoul (KR)

(73) Assignee: **Samsung Electronics Co., Ltd.**,
Suwon-si (KR)

(**) Term: **14 Years**

(21) Appl. No.: **29/495,301**

(22) Filed: **Jun. 30, 2014**

(30) **Foreign Application Priority Data**

Jan. 3, 2014 (KR) 30-2014-0000517

(51) **LOC (10) Cl.** **14-04**

(52) **U.S. Cl.**

USPC **D14/485**; D14/486; D14/488

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design. The broken lines are for environmental purposes only and form no part of the claimed design.

1 Claim, 1 Drawing Sheet
